UNITED STATES PATENT OFFICE.

HENRY ODEEN, OF PALO ALTO, CALIFORNIA.

PURIFICATION OF OILS.

No Drawing.

Application filed July 14, 1926. Serial No. 122,504.

This invention has to do with a process of refining oils and oil emulsions and more particularly the refining of fatty oils containing free fatty acids, and in its broader aspect 5 includes the steps of adding to and mixing with such oils a finely divided solid material carrying a dry alkali and adding at any stage of the process sufficient water to promote a rapid neutralization of free fatty 10 acids and to agglomerate the resultant soap stock.

One of the more important features of my invention resides in the employment in the process of a dry reagent or dry chemical 15 which consists of a finely divided solid material carrying a dry substance, such as a dry alkali, capable of acting upon and neutralizing the free fatty acids of the oil. The finely divided material may be inert and 20 non-absorbent and the dry reagent may be formed, for example by thoroughly mixing the inert non-absorbent material in powdered form with a concentrated solution of the alkali, such as caustic soda, drying the said 25 mixture, and grinding or pulverizing the resulting cake to a relatively fine powder. The surfaces or substantial portions thereof of the particles of powder will therefore be 30 coated with and carry a closely adherent thin film of dry alkali. This dry powder will hereinafter be referred to, for brevity, as "dry chemical." So formed the dry chemical, when added to the oil, is in an ideal state or condition not only to remove coloring, mucilaginous colloidal and finely 35 divided suspended matters, but also, when in the presence of water, to enable the reaction between the alkali and the acid components of the oil to proceed with avidity. However, 40 I prefer, for reasons more fully pointed out hereinafter, to employ a finely divided solid material which will absorb and to some extent be impregnated with the alkali in the step of forming the dry chemical, and I 45 shall describe my invention in detail in connection with such a finely divided solid absorbent material impregnated with a dry alkali. My process is also applicable to the 50 refining of the fatty oils in which a substantial proportion of fatty acids have been previously removed and in which process the alkali carried by the finely divided solid material serves to further purify the oil with 55 respect to its coloring, colloidal, mucilaginous and finely divided suspended matters,

as well as neutralizing and removing such free fatty acids as are present.

It may be stated at this point that if there is present in the oil, which is rarely the case, a sufficient amount of water to satisfy the 60 process, or an excess (e. g. if it is desired to treat an emulsion, i. e. oil carrying several percent of water in emulsified condition), then it is only necessary to add to such an oil the dry chemical in an amount sufficient 65 to combine with and remove the free fatty acids and the other impurities, and the soap formed in this reaction will also remove certain excess amounts of water. It is preferable, in such a case, to add such an amount 70 of the dry chemical that all the water will be removed from the oil. In its broadest aspect my invention, therefore, does not necessarily contemplate the addition of water where a sufficient amount thereof already 75 exists in the oil to be refined. In all cases where water is to be added to the fatty oils, except where it is desirable to leave a colored oil as in the case of salad oils, I prefer to first add and thoroughly mix the dry 80 chemical with the oil to be treated so as to obtain the beneficial results of a previous scrubbing action upon the oil and thus secure a more complete removal of the coloring, colloidal, mucilaginous and finely 85 divided suspended matters.

The present invention relates to and involves what will herein be termed a "dry" process, since, while water is used in the operation, it is practically all absorbed by 90 the reaction products and by the dry chemical added. In practice the process involves the use of a limited amount of water so that it will be within the absorptive capacity of the reaction products, and the use of a dry 95 chemical to produce the reactions and assist in absorbing the water. The soap is the principal reaction product and this together with the precipitated coloring, colloidal and finely divided suspended matters are left 100 closely adherent to and entangled with the residue of the dry chemical in a substantially solid agglomerated state at the conclusion of the treatment, whereas in the commercial processes heretofore generally used industrially, enough water is present so that these soaps and similar products existed as liquid solutions at this stage, hence these prior processes can be termed "wet" processes. It 105 is on account of their solid form and due to 110

the absence of excess water that the said soap products and other impurities are rendered more insoluble in the oil, causing the same to be more readily precipitated and be very easily removed in the entirety from the purified oil in my improved process, and this I consider to be an important achievement. I will now describe in detail what I consider to be the preferred embodiment of my invention.

The present invention specifically contemplates the use of a dry form of alkali or neutralizing agent (preferably caustic soda because of its comparatively low cost) existing in the form of a dry thin film or coating over the surface of, and preferably to some extent deposited within the pores or interior of some suitable dry finely divided solid material, preferably an inorganic absorbent material such as fuller's earth or pulverized pumice stone. Pulverized charcoal can be used as the absorbent, if desired. Limited amounts of water are ordinarily added to the oil during the operation (e. g. before, during or after the addition of the pulverulent material, but not pre-mixed therewith) to aid and hasten the reaction between the alkali and the acid components in the oil, and this addition of water also serves to so control said reaction so that the alkali is prevented from saponifying any appreciable amount of neutral oil but is confined to the neutralization of acidity and the removal of other impurities. If no water were added during the process and only the usual traces of moisture found in crude oils were present, the reaction would be extremely sluggish and would not proceed to completion for a long period of time, but the instant that water makes contact with alkali, the reaction proceeds with avidity and this takes place between the alkali and the acid components because of the latter's greater affinity for alkali than that existing between neutral oil and alkali. However fatty oils are readily saponifiable by caustic alkalies if any considerable amount of moisture is present; therefore in this method the amount of water introduced into the operation is so limited as to supply the needs of the process only, and the amount of water added is capable of being absorbed by the dry reagent added, and the solid reaction products including the soap. By thus controlling the reaction a more nearly quantitative separation of acid components can be effected than by using an excess of aqueous solution of alkali which is the common method employed in the practice of the art.

A slight excess of free water which necessarily would be present or added during the operation would not be available for the saponification of any substantial amount of neutral oil because of the presence of the

dry chemical and reaction products which have dehydrating properties. The films of soap which are formed in the reaction assist in the dehydration of the oil after the essential reaction has taken place. The dry chemical itself dehydrates in a powerful way. There is also the absorption of moisture taking place within the pores of the carrier material through capillary action if this carrier is of an absorbent character. This process then, properly controlled, will produce an oil substantially free from moisture. It is understood that during the neutralizing operation agitation is employed so that there is uniform distribution of the neutralizing agent throughout the mass of the oil being treated.

Another noteworthy advantage of this method in all of its embodiments is that it will remove more coloring, mucilaginous, colloidal, and finely divided suspended matters existing in the oil before or during treatment, than will the ordinary wet neutralizing methods. This may be partly due to the cauterizing action of the caustic alkali existing in such active state, and in my preferred embodiment partly due to the increased insolubility of the reaction products which inhibits distribution of color, and other impurities.

By the use of my method, oil-washing and oil-drying equipment is not needed, and the bleaching equipment can be much simplified, thus lending to considerable economy in the apparatus used.

The present invention is broadly applicable to fatty oils in general, including those oils which are solid at normal temperature as well as those oils which are liquid at normal temperature, and the term "oils" is intended to cover both normally liquid oils and normally solid oils and fats. The present application is particularly concerned with liquid fatty oils of animal and vegetable origin; for example, cotton seed oil, corn oil, castor oil, rape oil, soy bean oil, cod liver oil, and various other liquid fish oils, (or marine oils), lard oil, and, generally, all liquid fatty oils from which it is desired to remove the free fatty acids, whether it is also desired to improve the color of the oils or not.

The present invention contemplates a distinctively dry process of refining oils, and while water is used, and is important in the process, the absorptive capacity of the absorbent neutralizing agent and reaction products formed (particularly the soap) is preferably substantially in excess of the total amount of water present or added during the process.

As in my prior application 727,543, filed July 22, 1924, of which the present case is a continuation in part, fuller's earth or other argilaceous material is generally the pre-

ferred absorptive material in the dry chemical used. Other carriers or vehicles such as kieselguhr, vegetable carbon or charcoal, animal charcoal, clay of various grades, 5 burnt clay, powdered coke and other inorganic absorptive materials can be used, or organic materials if desired, such as soap or perhaps sawdust or wood meal, especially from non-resinous soft porous woods, can 10 be used, as well as inert carriers which are not substantially absorbent e. g. sand. Anhydrous salts or those partially hydrated and capable of taking up additional water of crystallization, such as sodium carbonate, 15 or sodium sulphate can likewise be employed as the carrier for the caustic alkali. Some of these materials, notably sodium carbonate, might be considered as not inert since they might exercise more or less neutralizing 20 action upon the free fatty acids. The vehicle obviously should be one which will not destroy the caustic soda added.

As stated, such a dry solid carrier material may comprise a soap, and in this modification, I may for instance apply to a concentrated liquid soap or molten soap, a proportion, preferably a large proportion of alkali, say caustic alkali, in the form of a hot supersaturated solution or dry caustic 30 alkali (e. g. powdered). This mixture of soap and alkali should be thoroughly mixed to produce a very homogeneous mass, and allowed to harden say by congealing or drying. The hardened soap-alkali mixture may 35 then be comminuted to a fine degree of subdivision in a suitable type of grinding equipment.

I have above referred to soda-ash as the vehicle, thus I may add to molten caustic 40 soda an equal proportion, more or less, of soda ash, and effect a homogeneous mixture, then cool to solidify the mass and grind to a fine state of subdivision.

As stated, water is employed in the process in an amount capable of promoting the reaction between the free fatty acids and the dry alkali, and ordinarily relatively pure water (e. g. ordinary tap water) is preferred. 45 However, the use of dissolved salts and dissolved substances in the water is not precluded. Thus it might be advisable to employ, instead of pure water, solutions of common salt, aluminum sulphate or borax, or other substances which may to some extent 50 precipitate or destroy coloring matter in the oil or which may to a considerable extent assist in dragging down and precipitating colloidal or suspended matters, or albuminous 55 matters or other gummy or mucilaginous substances present in the oil. Thus a 5 to 10% solution (or a stronger or weaker solution) of any of these salts can be used instead of water, in the above example.

The amount of water to be used in the 60 process will vary, depending largely upon

the quantity of free fatty acids present in the oil. With oils of ordinary free fatty acid content (say 3 to 7% free fatty acid content) an amount of water equal to 0.5% up to 2% or 2.5% will generally be satisfactory, although somewhat larger amounts than this may be used if desired. In some cases commercial crude fatty oils (say cotton seed oil) frequently contain more or less water, say up to 0.5% or even up to 1%. 70 With oils naturally containing such quantities of water, and especially if the free acid content is low, it may not be necessary to add further amounts of water during the process. Generally stated, I find it advisable to add more water if the oil is high in free fatty acid content than would be used if the oil is low in free fatty acids. Thus with a 5% F. F. A. content oil, I may use about 2% of water, and with a 10% F. F. A. 80 content oil, it may be necessary to use as much as 3.5 to 4% of water. (The percentages stated in this paragraph, and elsewhere in the case, are of course based on the amount of oil.) 85

The amount of water above stated can be varied between more or less wide limits. In treating cotton seed oil, for example, the water can be all added before the introduction of the dry chemical, or can be added 90 after the addition of the dry chemical, or can be added during the addition of the dry chemical, but separately therefrom. I do not mix the water with the dry chemical and add the said mixture to the oil to be treated, 95 since this would be wasteful and I would not get the complete results of the process.

Reference was made above to adding water first, and later adding the dry chemical. Thus in producing a salad oil from crude 100 cotton seed oil, containing say 0.2% of water and 0.6% of free fatty acids, I might first add 1% of water to the oil, while well agitating, to form an emulsion, and then dump in say 1.5% of the dry chemical, continue 105 agitation for half an hour, and filter. This would leave a substantial proportion of the original coloring matter in the oil, but remove the free fatty acids, colloidal and gummy matters, water, etc., and some of 110 the color.

Preferably the amount of the dry chemical used (say fuller's earth impregnated with dry caustic soda) should be capable 115 (assisted by the soap formed in the process) of absorbing considerably more water than the total amount employed or present during the process, and under ordinary conditions the amount of the dry chemical to be used will depend on numerous factors, including the amount of free fatty acids in the oil to be treated, the amount of decolorization to be effected and the amount of mucilaginous and gummy materials in the oil. 120 For ordinary purposes 2 to 5% (based on the 125 oil) will be sufficient.

amount of the oil) will be found to be a convenient amount of the dry chemical to use, but in some cases, particularly where it is desired to produce a considerable amount of decolorization of the oil, I may use 10% or even more.

The amount of active neutralizing reagent, say caustic soda, should preferably be somewhat in excess of the amount which theoretically would be necessary for combining with and neutralizing the total free fatty acids in the oil under treatment if it is desired to completely remove such acids.

The dry chemical which I prefer to use is preferably formed by impregnating a dry inert absorbent material, such as fuller's earth or any of those above referred to, with a solution, preferably a highly concentrated solution, of caustic soda, then I dry the so impregnated material, for example in an oven at a temperature of 200 to 300 or to 400° F., or, if desired, much higher temperatures can be used. With 100 parts of ordinary fuller's earth, I may use 130 parts of a saturated (say 55%) solution of caustic soda. The material is thereafter dried and the resulting cake is ground up or pulverized to a relatively fine powder. In other cases, with 100 parts of fuller's earth satisfactory materials have been prepared when using from 80 to 150 parts of saturated caustic soda solution or weaker solutions, containing 10-45% NaOH, more or less.

I have referred above to drying the impregnated fuller's earth, but it is to be understood that this drying does not have to be complete to the extent of removing every trace of water. The material is preferably dried sufficiently so that it will readily absorb and take up water present in or added to the oil. The term "dry" will be so understood herein.

Complete impregnation in the manner described, followed by drying, gives a satisfactory chemical to use. However in some cases, caustic soda and fuller's earth can be well ground and triturated together, say in a mortar or edge-runner mill. If the mill is open to the atmosphere the caustic will take up more or less moisture from the atmosphere during this step, or some water can be added to the mass before or during the grinding and mixing operation. Thus this will give an intimate association and substantially an impregnation. This product can be then dried and powdered, as above described.

In practicing the method of oil refining and purification in its preferred form, I generally warm up the oil to a temperature at which it is freely liquid and at which it has a sufficiently low viscosity to be readily treated. This temperature will depend

upon the particular oil, and with cotton seed oil a temperature of 90° to 100° F. is very satisfactory. Irrespective of the particular oil, I preferably do not heat to over 140° F., at and above which the heat is likely to "set" the color and otherwise injure fatty oils. The alkali impregnated solid material (or "dry chemical") is then added to the oil, for example by being sifted or sprinkled upon the top of the agitated body of oil and is preferably agitated during and for some time after this dry chemical has been added. The water to be used is preferably added at this stage, and the "break" will occur after only a few minutes further agitation. The oil and materials contained therein are then allowed to settle and sedimentation will occur quite rapidly. Even in a large bulk of oil it will be found that the solid matter will practically all settle out of the oil, within half an hour or an hour, and the clear oil in the upper part of the receptacle can then be passed through the filter press (or other separating device) and sent to storage tanks as refined oil. I call attention to the fact that the sedimentation here referred to may be complete in a half hour or an hour instead of requiring many times this period as is the usual case in wet methods of refining.

Due to the thorough drying or dehydrating action taking place in the process, the filtered refined oil will be found to be very bright and clear and free from soap, and analysis will show practical absence of water therein, or say usually well below 0.25% and in most cases below 0.1% of water.

The sludge in the bottom of the receptacle can be drawn off and this will carry more or less entrained oil and a large part of this can be separated from the solid material in a centrifugal basket separator or other suitable device. This oil can then be passed over to the filter press above referred to. The remaining solid material can be worked up in any desired manner, for example by agitating with hot water and dissolving the soap stock which latter may be disposed of in any desired manner. The fuller's earth, when that substance is employed as a carrier for the alkali, does not, of course, dissolve in water during the separation of the soap therefrom, and this fuller's earth can again be impregnated with caustic alkali and re-used in the process. Thus the fuller's earth or similar carriers can be reused many times.

When other solid chemically inert insoluble carriers are employed, the above mode of regenerating same for reuse, will be satisfactory. When anhydrous soda or soap powder is used, the solid material from which the oil has been removed can be sold as soap stock. When powdered abrasive

such as kieselguhr or pumice is used as the carrier, the product can be usefully incorporated into scrubbing powders, etc.

In the process of refining, as herein described, it is generally an object to remove the free fatty acids as completely as possible. However in some instance it would be sufficient to use far less than enough of the dry chemical and of water to accomplish this. Thus a highly colored and highly odiferous oil might be treated with only enough of the dry chemical and water, to somewhat brighten its color and remove some of its odorous substances while removing only half or less of its free fatty acid content to cheaply improve a soap-making oil.

In a modified form of the process, I may add somewhat more water, even continuing the addition of water after the "break" say while agitating. Thus I might use twice as much water (more or less) as is needed for effecting the reaction. I can then settle and decant or filter, if desired, although these operations at this stage are unnecessary. I can then suitably remove the excess of water, e. g. by adding more of the alkaline absorbent reagent followed by a short agitation and filtration. This modification may sometimes produce more bleaching or more complete removal of colloidal or suspended matters, but is not generally recommended.

In another modification of the process, I can add alternately several small amounts of water and of the dry chemical while agitating, until the desired amount of purification has been effected, and the oil may or may not be filtered, after each addition of chemical has had a chance to effect the desired purification. In this way, a minimum amount of chemical would effect a maximum amount of purification. Such a modification however might cost more in the way of added handling. Thus I may add the above stated amounts of chemical and water, (or smaller amounts, if preferred) in all, but these can be added in several fractions, alternately, instead of being all added at once.

In a particular example of the modification referred to in the last paragraph, I may add say one-half of one percent of water to cotton seed oil containing two percent fatty acids, stir thoroughly and add say one-half of one percent of the dry chemical under agitation. Continue agitation for 10 minutes, then add another one-half percent of water, followed by the addition of another one-half percent of dry chemical, all under continued agitation which is continued for say, another 15 to 30 minutes, then separate the resultant soap-stock.

I have referred above to the use of caustic soda as the preferred neutralizing reagent.

Other alkalis such as the carbonates, oxides, and hydroxides of the alkali metals and alkaline earth metals, or ammonia gas, or salts of weak acids which give a basic reaction, such as borates, silicates, or other agents capable of neutralizing free fatty acids, can be used.

I have also referred to the use of strong solutions of alkali for impregnating the carrier materials. In some cases however, relatively weak solutions or impregnation with only a small amount of alkaline solutions may be advisable. Thus I may prepare "dry chemical" containing only 2 to 10%, more or less, of NaOH, which would be very suitable when it is more especially desired to accomplish decolorization, precipitation of colloidal matters, etc., with only a small amount of neutralization of free fatty acids, as when treating oils in which the fatty acid content is quite low. An example of this is the treatment of cocoa fat from which it is desired to remove a large amount of coloring matters, colloidal suspended matters, etc. although the free fatty acid is usually very low. For ordinary purposes however, as where the removal of a normal fatty acid content is desired, the amount of NaOH in the dry chemical may be higher, say from 10% up to 45%, more or less.

In one of the above examples, I have discussed the drying of the impregnated absorbent, e. g. fuller's earth. When soap powder is used as the absorbent, I may make a mixture of soap, alkali and water in any desired proportions (e. g. 10:8:5) and dry this mixture say in a vacuum drier, to eliminate the use of high temperatures. This dried material is then reduced to the desired state of fineness.

The advantages of my invention are: (a) The yield of neutral oil from the refining steps is very greatly increased because the dry process practically precludes the formation of emulsions. In the ordinary methods of refining, this neutral oil loss is one of the greatest, and oftentimes the greatest item of refining cost, but by my method this refining loss is materially reduced. (b) The absorption losses in the bleaching and filtering step of the wet process methods are reduced to a fraction thereof because in my method the clear oil from the neutralizer tank may be run directly to the filter presses without the addition of decolorizing clays or carbons which absorb notable proportions of oil, thus eliminating these absorption losses and thereby also increasing manyfold the number of batches that may be run through the filter press before its capacity has been reached. (c) Lower cost, (as compared with other purification processes) because of less labor and equipment required to carry on the process, and because of a

greater yield of neutral oil. (d) A further substantial reduction in cost and simplification of the whole process is effected by the decolorizing action taking place in the same stage with the neutralization of the free fatty acids. (e) A great saving in time is effected, since washing and subsequent settling are eliminated. (f) It becomes unnecessary to subject the oil to high drying temperatures, thereby insuring a better quality of oil, particularly when the same is to be used for edible purposes. (g) It practically precludes the formation of free fatty acids in the oil under treatment since the oil during processing does not encounter the usual washing and high heating steps. (h) The neutral oil is practically completely freed of soap in one operation. (i) The working up of the soap stock is simplified because of the practical absence of emulsions, which are always a source of large refining loss, and cost of handling. (j) The process presents especial value in the treatment of certain oils, such as castor oil, which, when subjected to the wet neutralizing methods, produce very troublesome emulsions or solutions, or both, in the refining kettle. My process completely eliminates the formation of such emulsions and solutions.

I have described in detail several embodiments of my invention but it is to be expressly understood that I do not limit myself thereto or to the details related in connection with the specific embodiments described. I have also indulged in some theoretical discussions of what actually takes place in the practical use of my invention to more clearly elucidate the principles thereof. I may be mistaken about some of these theoretical considerations but I do know that when the steps of the process are carried out in the manner clearly indicated no difficulties will be encountered in practicing my method and that substantial results, some of which have been referred to, will be achieved.

In a concurrently filed application 122,505, I have claimed, in particular, the application of this process to normally solid fatty oils, and also the addition of the water after the addition of the dry chemical.

What I claim and desire to secure by Letters Patent is:

55 1. A process of refining normally liquid fatty oils from which the free fatty acids have not been removed, which comprises the steps of adding to and mixing with such oils a dry, finely divided, alkali-impregnated reagent, and adding at any stage of the process sufficient water to promote a rapid neutralization of free fatty acids therein and to agglomerate the resultant soap stock, the amount of water being insufficient to

leave any substantial proportion of soap 65 in solution.

2. A process of neutralizing acidity in a fatty oil emulsion containing a percentage of water which is only a minor fraction of the amount of the oil and of removing the water 70 therefrom, and of removing colloidal substances and finely divided suspended matters therefrom, which comprises the steps of thoroughly distributing into said fatty oil emulsion while carrying sufficient water to 75 promote reaction, a finely divided solid reagent comprising a solid material carrying a solid alkali intimately bonded thereto, which reagent is capable of abstracting water from such oil emulsion, in an amount sufficient to 80 neutralize the fatty acid content of such fatty oil emulsion, whereby the oil is neutralized and brightened, and colloidal, suspended matters are removed, and the water is substantially all removed therefrom, and thereafter separating the remaining dry purified fatty oil from the insoluble matter. 85

3. A process of refining vegetable and animal oils containing substantial amounts of free fatty acids, which comprises the steps of 90 adding to such oils water in limited quantity and adding a substance comprising a finely divided substantially dry solid agent carrying thoroughly incorporated therewith a dry neutralizing reagent to neutralize free fatty acids and to take up coloring and resinous matter present in the oils, the amount of said dry neutralizing reagent being more than chemically equivalent to the free fatty acids in the oils, and the amount of the 100 added water being insufficient to leave any substantial amount of the soap in a liquid state in said oil. 95

4. A process of refining fatty oil which comprises the steps of adding to fatty oil 105 from which the free fatty acids have not been removed, water and thereafter a substantially dry pulverulent intimate mixture of a solid material carrying an alkali, both in amounts sufficient to convert the free 110 fatty acids into solid soap and to produce a neutral oil, and thereafter separating the insoluble solid materials from the oil.

5. A process of refining vegetable and animal oils containing substantial amounts of 115 free fatty acids, which comprises the step of adding to such an oil a small percentage of water and while below 140° F., and adding to said oil a quantity somewhat in excess of that theoretically required of substantially dry fixed alkali carried in a finely divided solid agent to combine with the free fatty acids present to produce soap and a neutral oil and to absorb coloring and resinous matter present in the oil. 120

6. In the purification of fatty oils containing substantial amounts of free fatty acids, the improvement which comprises 125

adding to such oil while warm, a small percentage of water and a dry reagent comprising a dry solid vehicle carrying a dry alkali intimately bonded thereto, in such amounts as will convert the free fatty acids contained in the said fatty oil into a soap which is closely attached to said solid vehicle, and thereafter separating the soap and insoluble material from the purified oil, the amount of water being not substantially greater than can be taken up by said dry reagent and the reaction products formed.

7. In a process of refining a fatty oil containing free fatty acids, the steps which include forming a warm mixture of such oil with a small percent of water, and adding a finely divided solid alkali-resistant material carrying dry fixed caustic alkali intimately bonded thereto, and agitating said mixture and material, and thereafter separating the insoluble matter from the oil.

8. In a process of refining a normally liquid fatty oil containing free fatty acids, the step which comprises adding to such oil while containing water in amount substantially less than the amount of free fatty acids, a finely divided solid material which is non-destructive of fixed alkali, carrying a dry fixed alkali intimately bonded thereto, in an amount sufficient to combine with such free fatty acids, and well agitating such materials together, the amount of such dry reagent being sufficient, in conjunction with the soap formed, to pick up substantially all the water present.

9. In a process of refining a fatty oil containing substantial quantities of free fatty acids the steps which include forming a warm mixture of such oil with an amount of water less than the amount of such fatty acids, and agitating same with a finely divided solid absorbing material carrying a dry fixed alkali in an amount sufficient to combine with such free fatty acids.

10. A process of neutralizing acidity in an emulsion of a normally liquid fatty oil and removing water, colloidal impurities and finely divided suspended matter therefrom, which comprises the step of adding a finely divided solid substance each particle of which is intimately associated with a dry agent capable of neutralizing such acidity, the amount of such added material, in conjunction with the reaction products formed, being sufficient to leave the oil substantially anhydrous.

11. In the purification of normally liquid fatty oil from which the free fatty acids have not been removed, the herein described improvement which comprises adding to said oil while the latter contains a small amount of water, and while at a temperature at which the oil is freely liquid but below 140° F., a reagent comprising a free solid alkali in a dry state intimately mixed with

a dry finely divided solid material, then thoroughly mixing such oil and reagent together the total amount of water present or added being not above the amount which can be taken up by said solid reagent and reaction products, whereby the free fatty acids of the oil become substantially completely combined with the said alkali, and the water becomes absorbed by the solid materials.

12. A process of refining cotton seed oil which comprises well mixing crude cotton seed oil having a normal free fatty acid content with a dry intimate mixture containing a dry alkali intimately bonded to a finely divided solid material compatible therewith, and activating the reaction substances by adding at any stage of the process, an aqueous liquid non-injurious to the alkali, capable of absorption by such solid materials and the reaction products.

13. A process of refining fatty oils which comprises treating a fatty oil containing free fatty acids with about 0.5 to 4% of water, and with about 2 to 10% of a dry reagent, such dry reagent comprising a solid absorbent material carrying intimately incorporated therein, a caustic alkali, the amount of such dry reagent and reaction products formed, being always sufficient to absorb the entire amount of water present in the oil and added, and the caustic alkali in said dry reagent added being in excess over the amount theoretically necessary to neutralize all the free fatty acids present in said oil, such water and dry reagent being added separately and in the order stated and the oil being at not above 140° F., during such treatment, and agitating the mixture.

14. A process which comprises treating a normally liquid fatty oil containing free fatty acids, with about 0.5 to 4% of water, and with not substantially above 5% of a dry reagent, such dry reagent comprising a solid material carrying intimately incorporated therein, a caustic alkali, the amount of such dry reagent being always sufficient, in conjunction with the reaction products to absorb the entire amount of water present in the oil and added and the caustic alkali in said dry reagent added being in excess over the amount theoretically necessary to neutralize all the free fatty acids present in said oil, such water and dry reagent being added separately but in any desired order, and the oil being at not above 140° F., during such treatment, and agitating the mixture.

15. In a process of refining a fatty oil whose acid components have not previously been removed, the step which comprises adding a small percentage of water to such oil and thereafter adding thereto a dry finely divided solid material, the particles of which carry a dry alkali intimately bonded thereto, the total amount of water present at any time during such treatment being sufficient

to promote rapid neutralization and to substantial amount of water, the step of adding ¹⁰ agglomerate the resultant soap stock without to and mixing with such an oil a finely causing appreciable emulsification, the water divided solid absorbent carrier material being only in such an amount as will be intimately associated with a dry alkali in an absorbed by the solid material and solid reaction amount sufficient to remove the impurities products yielding an oil which is substantially anhydrous. and all of the water from the oil. ¹⁵

16. In a process of refining fatty oils containing free fatty acids and a small but sub-

In testimony whereof, I have hereunto set my hand this 13th day of July, 1926.

HENRY ODEEN.
